Primary Examiner — Antoine D Davis(74) *Attorney, Agent, or Firm* — Stephen R. Valancius(57) **CLAIM**

The ornamental design for a stud sensor, as shown and described.

DESCRIPTION

FIG. 1 is a perspective view of a construction laser showing my new design;

FIG. 2 is a top plan view thereof;

FIG. 3 is a rear view thereof;

FIG. 4 is a right side view thereof;

FIG. 5 is a left side view thereof;

FIG. 6 is a front view thereof; and,

FIG. 7 is a bottom plan view thereof.

In the above drawings, the broken lines and the areas within the broken lines form no part of the claimed design.
